By *Fricker & Bush*,
Attorneys.

UNITED STATES PATENT OFFICE

OLIVER C. RITZ WOLLER, OF CHICAGO, ILLINOIS

ACCELERATOR PEDAL

Application filed October 9, 1930. Serial No. 487,415.

My invention relates to accelerator pedals for automobiles, and it has for its object the provision of a new and improved form and arrangement of parts by reason of which I may provide the utmost of ease and comfort for the driver of a car equipped with my improved device. When a driver applies pressure upon an accelerator pedal for hours at a time with little or no rest or change, there is a distinct tendency for the foot to become tired or even cramped so as to increase the difficulty of properly controlling the car and very materially increasing the danger of driving. For this reason, it is the object of my invention to provide a form of pedal by which the pressure between the pedal and the driver's foot may be distributed as evenly as possible without danger of any marked concentration of pressure at any one point, by which the transmission of the vibration from the car to the foot of the driver through the pedal may be prevented to a large extent, by which the foot may be largely protected from the heat of the engine, and by which the difficulty of continued pressure on the pedal may be otherwise lessened.

It is one of the objects of my invention to provide an improved form of cushion, together with improved means for securing such cushion in operative position on a pedal and for protecting the cushion against wear without detracting too much from the cushioning effect.

It is another object of my invention to improve devices of this type in sundry details hereinafter pointed out. The preferred means by which I have accomplished my several objects are illustrated in the drawing and are hereinafter specifically described. That which I believe to be new and desire to cover by Letters Patent is set forth in the claims.

In the drawing,

Fig. 1 is a top plan view of the preferred form of my improved pedal;

Fig. 2 is a side view of the device as shown in Fig. 1;

Fig. 3 is a bottom plan view of the cushioning means employed as a part of the device of Fig. 1;

Fig. 4 is a vertical sectional view, taken substantially at line 4—4 of Fig. 3;

Fig. 5 is a vertical sectional view taken at line 5—5 of Fig. 1; and

Fig. 6 is a view similar to a portion of the device as shown in Fig. 3 but showing a modified form of construction.

Referring now to Figs. 1 to 5 inclusive in which corresponding parts are indicated by the same reference characters, 10 indicates a plate formed of sheet metal having a reinforcing plate 11 secured thereto at one end, such reinforcing plate 11 comprising one of the leaves of a hinge by which the plate is pivotally mounted upon a bracket 12 which is adapted to be secured upon the floor boards of a car in position for causing the pedal to rest upon the accelerator of the car. The pedal is pivotally connected with the bracket 12 by means of a pin 13 extending through lugs 14 carried by the plate 11 and lugs 15 carried by a hinge plate 16 which is secured by welding or otherwise with the bracket 12. A coiled spring 17 mounted upon the pivot pin 13 and connected with the hinge plates serves to hold the pedal normally in position swung to the limit of its motion toward the hinge plate 16. The bottom plate 10 is reinforced on its bottom face by a plate 18 preferably secured by spot-welding thereto.

As is best shown in Fig. 5, upon the bottom plate 10 I have provided a sheet 19 of asbestos, upon which in turn I mount my improved cushioning means. In the construction shown in Figs. 1 to 5, my improved cushioning means comprises a covering and enclosing member 20 formed preferably of rubber. The member 20 comprises a sheet of rubber 21 having walls 22 extending entirely about its edge. The wall 22 at its edge portion located away from the sheet 21 is provided with an outwardly extending flange 23. At one end portion, a plurality of walls or ribs 24 extend across between the oppositely disposed walls 22, such ribs 24 being formed integrally with the walls 22 and standing in diagonal position with respect to the facing portion 21. At its opposite end, the member is provided with a recess 25 adapted to receive a soft yielding pad 26 therein. The preferred form

of pad 26 is made of sponge rubber, being cut from a sheet of such rubber of uniform thickness so as to fit within the recess 25.

In the construction shown, the covering 5 and enclosing member 21, with the pad 26 in position in the recess 25 thereof, is held in position upon the plate 10 and asbestos sheet 19 by means of a metal rim member 27 formed preferably of polished sheet aluminum pressed into form, adapted by engagement with the flange 23 and the edge portions of the plate 10 to hold the parts securely in operative engagement with each other. The asbestos sheet 19 interposed between the plate 10 and the rubber tread serves to protect the driver's foot from the heat of the engine. The sheet 19 also protects the cushioning means of the tread from excessive heat and insures longer life and greater resiliency of 20 the tread.

With the parts secured in position as shown in Fig. 5, it will be appreciated that the facing member 21 is spaced from the metal plate 10 at one end by the sponge rubber pad 26 and at the opposite end by the ribs 24. It will be understood that upon the application of pressure to the covering member 20, the ribs 24 by which the space at one end is divided into cells or compartments 30 will be collapsed upon each other serving more or less to compress the air in such cells. At the opposite end of the device, the pressure upon the covering member 20 serves to collapse the walls of the cells of the pad 26, 35 serving necessarily to compress the air within the myriad cells of the sponge structure.

By the provision of my construction as shown and described, I am enabled very readily to provide a highly desirable form of cushioning means. The covering member 20 40 is preferably formed by a casting or molding operation so as to receive the pad 25 which can be prepared by a simple stamping operation from sheet form. At the end of 45 the device at the left as shown in Fig. 4, where the necessity for a very soft pad is not so great, and where it is desirable that the thickness of the pad be decreased, I have provided the yielding rib arrangement comprising the parts 24 which may be cast integrally with the covering member 20.

In Fig. 6, I have provided a covering member 28 similar to the member 20, except that the ribs 24 are eliminated and a different arrangement is substituted. In the construction as shown in said Fig. 6, a series of ribs 29 are provided in crossed relationship to a second series of ribs 30, such ribs being formed integrally with the side walls 31 of the structure and being arranged in substantially perpendicular position with respect to the sheet portion 32 forming the facing for said member 28. When pressure is applied upon the facing member 28 downwardly 55 upon the ribs 29 and 30, such ribs are adapted

to buckle horizontally for providing the desired resilient support for such facing portion of the cushioning means.

While I prefer to employ the form of construction as shown in my drawing and as above described, it is to be understood that my invention is not limited thereto except so far as the claims may be so limited by the prior art, it being understood that changes may well be made in my device without departing from the spirit of my claims.

I claim:—

1. In an accelerator pedal, the combination of a plate, means for pivotally mounting said plate in position on a car, a covering member formed of rubber extending along said plate having a recess in its inner face at one end portion and having flexible rib portions formed integrally therewith at the other end portion serving to space said member yieldingly from said plate, a pad of sponge rubber removably mounted in said recess for supporting said covering member yieldingly from said plate, and means for securing said covering member on said plate. 90

2. In an accelerator pedal, the combination of a plate, means for pivotally mounting said plate in position on a car, a covering member formed of rubber extending along said plate having a recess in its inner face at one end portion and having flexible rib portions formed integrally therewith at the other end portion and standing in oblique position with respect thereto serving to space said member yieldingly from said plate, a pad of sponge rubber removably mounted in said recess for supporting said covering member yieldingly from said plate, and means for securing said covering member on said plate. 95

3. In an accelerator pedal, the combination of a plate, means for pivotally mounting said plate in position on a car, a covering member formed of rubber extending along said plate having a recess in its inner face at one end portion and having flexible rib portions formed integrally therewith at the other end portion serving to space said member yieldingly from said plate, a pad of sponge rubber removably mounted in said recess for supporting said covering member yieldingly from said plate, said covering member having outwardly projecting flanges at its sides, and rim means adapted by engagement with said flanges and the marginal portions of said plate to hold the pad and covering member in position on the plate. 110

4. In an accelerator pedal, the combination of a plate adapted to be pivotally mounted in position on a car, a covering member formed of compact rubber extending along said plate and having a recess in the under side of its forward portion, the rearward portion of said covering member being of reduced thickness as compared with its for- 125 130

ward portion and having flexible rib portions formed integrally therewith on its under side and serving to space the rearward portion of said member yieldingly from said plate, a pad of sponge rubber removably mounted in said recess for supporting the forward portion of said member yieldingly from said plate, and means for securing said covering member on said plate.
